UNITED STATES PATENT OFFICE

ABRAHAM M. BABITCH, OF FLINT, MICHIGAN, ASSIGNOR TO A C SPARK PLUG COMPANY,
OF FLINT, MICHIGAN

OIL PURIFIER AND DILUTION REMOVER

Application filed March 28, 1927. Serial No. 179,018.

This invention relates to apparatus for the purification of lubricating oil and particularly to a design suitable for use upon internal combustion engines to clean the engine oil supply by removing foreign particles and diluents such as fuel and water. It has heretofore been proposed to pass the oil through a distillation chamber heated by the exhaust gases and in this manner accomplish the removal of liquid diluents. In order to remove foreign particles I have combined with such a system an oil filter of conventional type so that the distillation and filtration take place in the same chamber. This insures that even in the coldest weather the oil will be of sufficiently high viscosity to render the filter effective.

With the system above described I have also combined means for ventilating the crank case. This I have accomplished by applying suction to the distillation and filtration chamber to remove vaporized diluents, and by connecting this chamber to the crank case vapors therefrom are drawn through the chamber preferably in contact with the returning oil effecting further evaporation of diluents. At the same time the crank case vapors carry their own content of diluents which is thus removed from the crank case prior to condensation and mingling with the oil.

Some or all of the above features may be employed. In addition I have incorporated in my system certain details of construction which will be briefly referred to. Thus I have connected the oil return pipe from the purifier with the usual oil filler opening provided in the crank case. I have as above described, made this pipe of sufficient size to permit both the return of oil and the flow of vapors from the crank case to the still. To cool the oil in its passage back to the crank case I have preferably provided the return conduit with cooling fins. To insure thorough heating of the oil in the purifier I have provided heat radiating fins extending inwardly from the walls of the still. To control the heating of the oil I have provided a valve in the conduit connecting the exhaust manifold with the heating jacket and

have connected this valve with the usual throttle valve in such manner that at closed throttle, there is a maximum flow of exhaust gases to the still and at wide open throttle there is a minimum flow of exhaust gases to the still. To remove distillates from the still I have connected it with an exhaust gas operated venturi preferably located in the conduit through which exhaust gases are discharged from the still. Obviously if desired, the venturi may be otherwise situated and may be operated by the fan blast; or, if preferred, intake suction may be used to remove diluents.

I have pointed out above the component parts of my improved system. Obviously various of these parts may be omitted, and the remainder may be combined in different ways. However, I prefer the complete system as herein set forth.

Figure 1 is a vertical section through a portion of an internal combustion engine showing, somewhat diagrammatically, my invention applied thereto.

Figure 2 is a side view of the apparatus shown in Figure 1.

I have indicated at 4 a portion of a conventional automobile engine having the usual cylinders and pistons, and a crank case indicated at 6. The crank case is provided with the usual oil filler tube 8. In Figure 2 I have shown the usual carburetor 10 which supplies combustible mixture to the cylinders through riser 12 and the usual manifold, not shown. The customary throttle valve 14 is provided in the riser to control the flow of mixture to the cylinders.

My oil purifying apparatus comprises a distillation and filtration chamber 16 in the form of a cylindrical casing having a conical bottom, and surrounded by a heating jacket 18 of corresponding shape. Member 20 serves as a cover for the assembly which is held together by bolts passing through overlapping flanges on the casing and jacket and through the cover. The cover 20 likewise supports the filter element 21 which is preferably of the well-known A-C type, described and claimed in the application of Charles W. McKinley, Serial Number 93,944, 100

filed March 11, 1926, now Patent No. 1,651,400, granted December 6, 1927. In this type of filter, oil is supplied to the interior of a coiled bag at the center of its convolutions through a suitable fitting such as shown at 22 to which oil is supplied by means of conduit 24 connected either directly or indirectly to the pressure side of the pump. Conduit 26 extends upward into the bottom 10 of the filtration chamber. At its lower end the conduit communicates with oil filler tube 8 the outer end of which is tightly closed by cap 27. The end of conduit 26 which projects into the chamber 16 is preferably provided with a series of perforations to permit the passage of purified oil into the conduit and thence back into the crank case.

The heating jacket is supplied with heating medium, preferably exhaust gases, 20 through conduit 28 in communication with the main exhaust conduit. The hot gases pass upwardly about the still and are discharged through conduit 30 which may lead to the usual muffler. Adjacent the point of 25 connection with the jacket the conduit 30 is formed to provide a venturi 32. A passage 34, of relatively small cross-section establishes communication between the venturi and the upper portion of the distillation 30 chamber 16.

To control the application of heat to the jacket I have provided a butterfly valve 36 in the conduit 28 and have connected the operating means for this valve with the operating 35 means for the throttle valve 14 by means of link 40. This connection is so made that as the throttle opens the valve 36 closes. By this means when the engine temperature is high as when it is running with wide open 40 throttle the flow of heat to the still is correspondingly reduced; and, conversely when little fuel is being consumed, the throttle being substantially closed, valve 36 is open permitting a maximum flow of gases about the 45 still.

To insure thorough heating of the oil in the still I have provided annular heat radiating ribs 44 projecting upwardly into the distillation chamber. These ribs impede the 50 flow of oil into conduit 26 and insure that it is thoroughly heated before it leaves the distillation chamber. With the oil thus heated to a rather high temperature it is usually desirable that means be provided to cool it on 55 its way back to the crank case to prevent overheating in successive passages through the still. I have indicated such means in the form of cooling ribs 46 on conduit 26.

The operation of the apparatus is as follows. During the operation of the engine, oil is supplied by the usual engine driven oil pump through conduit 24 to the filter 21. In passing through the filter the flow of oil is retarded so that the heating time is lengthened thereby insuring better separation of

diluents. After passing through the filter the oil passes to the bottom of the filter chamber 16 and after cascading overheating ribs 44 passes into discharge pipe 26 thence through the oil filler pipe 8 to the crank case. 70 During the passage of the oil through chamber 16 it has been exposed to the heating action of the exhaust gases supplied to jacket 18 through conduit 28 and discharged through conduit 30. The distillates are 75 drawn off through passage 34 into the exhaust operated venturi 32. Owing to the low pressure thus created in the distillation chamber 16 crank case vapors are drawn up 80 through discharge conduit 26 into the chamber and pass off through conduit 34 with the distillation. The method of regulation of the application of heat to the still has been described.

Various modifications of the construction 85 have been indicated above and it is obvious that many others are possible in practice as suggested by the scope of the appended claims.

I claim:

1. In an engine having a lubricating system including a crank case, the combination of a distillation chamber, means for supplying oil from said system to said chamber, a conduit for returning purified oil from the 65 chamber to the crank case, an oil filter in said chamber and in the path of flow of the oil, and a suction connection for withdrawing vapors from said still, said conduit being of sufficient size to permit the passage of vapors from the crank case into the chamber. 100

2. The combination of claim 1, said suction means comprising an exhaust operated venturi.

3. The combination of claim 1, and means for heating the chamber comprising a jacket about said still, a conduit for leading exhaust gases to the still, a conduit for the discharging of gasses from the jacket, and said suction means comprising a venturi arranged 105 in said discharge conduit, and a connection from said chamber to said venturi. 110

4. An internal combustion engine having a lubricating system, a crank case, an exhaust conduit, an intake conduit, a throttle valve in 115 said intake conduit, a distillation chamber, means for conducting oil from said system into said chamber, a conduit for returning purified oil to the crank case, a conduit for leading exhaust gases about said still, means for withdrawing diluents from said still, a throttle valve in said last named conduit, and means connecting said throttle valves causing the first to open as the second closes, and vice versa. 120

In testimony whereof I affix my signature.
ABRAHAM M. BABITCH.
